US0D1075962S

(12) **United States Design Patent** (10) **Patent No.:** **US D1,075,962 S**
(45) **Date of Patent:** **** May 20, 2025**

(54) **TOY BUILDING BLOCK**

(71) Applicant: **Xidi Huang**, Shantou (CN)

(72) Inventor: **Xidi Huang**, Shantou (CN)

(**) Term: **15 Years**

(21) Appl. No.: **29/894,248**

(22) Filed: **Jun. 8, 2023**

(30) **Foreign Application Priority Data**

Dec. 12, 2022 (CN) 202230830879.8

(51) **LOC (15) Cl.** **21-01**

(52) **U.S. Cl.**

USPC **D21/594**; D21/493; D21/621

(58) **Field of Classification Search**

USPC D9/614; D11/160; D20/31; D26/99;

D21/483, 493, 576, 578, 585, 594, 621

CPC A63H 33/00; A63H 33/088; A63H 33/108;

A63H 3/04; A63H 3/16

(57) **CLAIM**

The ornamental design for a toy building block, as shown and described.

DESCRIPTION

FIG. 1 is a first perspective view of a toy building block showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

The broken lines shown in the drawings depict portions of the toy building block that form no part of the claimed design.

1 Claim, 8 Drawing Sheets
